G. T. BURNETT

BATHHOUSE SHOE

Filed April 2, 1923

UNITED STATES PATENT OFFICE.

GEORGE T. BURNETT, OF ZEIGLER, ILLINOIS.

BATHHOUSE SHOE.

Application filed April 2, 1923. Serial No. 629,297.

To all whom it may concern:

Be it known that I, GEORGE T. BURNETT, a citizen of the United States, residing at Zeigler, in the county of Franklin and State 5 of Illinois, have invented certain new and useful Improvements in Bathhouse Shoes, of which the following is a specification.

In carrying out the present invention, it is my purpose to provide a highly improved 10 form of shoe, especially adapted to be worn by bathers in bath houses, and the like, for effectively preventing slipping of the bathers upon the bath house floors, and also as a means for preventing the feet from becoming 15 wet or dirty.

A further purpose is the provision of such a shoe that is comparatively simple of construction, inexpensive of manufacture, and of such a nature as to be readily applied to 20 or removed from the feet.

To the attainment of the foregoing, the invention consists in the improvement as hereinafter described and definitely claimed.

Figure 1 is a side elevation of my improved shoe attached to the foot.

Figure 2 is a top plan view thereof, partly in cross section, the securing strap being fragmentarily shown.

Figure 3 is a longitudinal cross section of 30 the shoe with the securing strap removed, and.

Figure 4 is a transverse cross section upon the line 4—4 of Figure 1.

Referring to the drawing in detail, the 35 shoe 5 embodies a single length of wood or other material compatible with the purposes of the invention, which includes a sole portion 6, instep 7 and heel 8.

The top surface of the shoe is so cut as to 40 conform to the curvature of the bottom of a foot, it being noted that the bottom surface of the sole portion 6 is somewhat rounded in

a longitudinal direction, as is also the heel portion 8, for facilitating extending.

The bottom surface of the sole portion 6 45 is concaved as at 9, for providing surface contacting edges 10 at opposite sides thereof, the purpose of this concavity being to eliminate the entire bottom surface of the shoe from engaging the wet floors of bath houses, 50 for consequently preventing the splashing of the water upon the opposite foot.

Within opposite sides of the shoe, and at a point slightly forwardly of the instep portion 7 are staples 11, to which are secured the ends of strap members 12 and 13. The free end of the strap member 13 carries a desirable form of buckle 14, while the free end of the strap member 12 is provided with a plurality of openings 15, for receiving the 60 usual tongue of the buckle, whereby the shoe may be snugly retained upon the foot.

In view of the above description, it will at once be apparent that I have provided a highly improved form of shoe, specifically 65 adapted to be worn by bathers and the like, and although I have herein shown and described the preferred embodiment of the present invention, it is nevertheless to be understood that minor changes may be made 70 therein, without departing from the spirit and scope of the invention as claimed.

Having thus described my invention, what I claim as new, and desire to secure by Letters Patent is:

In a shoe of the class described, a single 75 length of wood comprising a sole, instep and heel portion, said sole portion being concaved upon its bottom surface at the toe and ball portion and being rounded in a longitudinal direction, and means for retaining said shoe upon the foot of the wearer.

In testimony whereof I affix my signature.

GEORGE T. BURNETT.
